RAILWAY SWITCH

Harry C. Jones, Magnolia, Ark.

Application November 15, 1949, Serial No. 127,344

4 Claims. (Cl. 246—428)

1

This invention relates to railway switches, and more particularly to an anti-clogging switch which will operate satisfactorily under adverse conditions, as when covered by snow or ice.

It is among the objects of the invention to provide an improved railway switch which will not be rendered inoperative by the accumulation of material, such as snow, ice, sand or mud, between its movable parts, but will remain freely operative at all times, which will safely support and guide trains passing thereover and can be easily secured to the conventional ties in association with conventional rails, and which is simple and durable in construction, economical to manufacture, and can be efficiently operated by existing switch stands.

Other objects and advantages will become apparent from a consideration of the following description and the appended claims in conjunction with the accompanying drawings, wherein:

Figure 1 is a top plan view of a railway switch assembly, illustrative of the invention;

Figure 2 is a transverse cross-section on the line 2—2 of Figure 1;

Figure 3 is a transverse cross-section on the line 3—3 of Figure 1;

Figure 4 is a longitudinal cross-section on the line 4—4 of Figure 1;

Figure 5 is a top plan view of a pair of support plates constituting operative components of the switch;

Figure 6 is a top plan view of a pair of slide plates constituting operative components of the switch; and

Figure 7 is a top plan view of the assembled switch with the movable parts in a different operative position from that illustrated in Figure 1.

With continued reference to the drawings, there is illustrated in Figures 1 and 7 a railway switch environment including a right-hand main-line rail provided in two longitudinally-aligned sections 10 and 11, the adjacent ends of which are spaced apart to receive switch mechanism therebetween, a left-hand rail including the two sections 12 and 13, the ends of which are spaced apart in a manner similar to the ends of the sections 10 and 11, the section 13 being bent outwardly near its ends to align with the left-hand rail of a side track. A right-hand side-track rail 14 is disposed adjacent and at an angle to the right-hand main-rail section 10 and terminates at a location along the rail section 10 spaced from the end thereof, and a side track left-hand rail 14 is disposed at the outer side of the left-hand main-rail section 12 and terminates

2

at a distance spaced from the end of the left-hand main rail 13 substantially equal to the distance between the ends of the right-hand main-rail sections 10 and 11. These rail sections are mounted upon transversely-extending ties 15, gauge plates 16 being interposed between the rails and the ties to hold the rails against spreading and having apertures therein receiving the spikes 17 by means of which the rails are secured to the ties in the usual manner.

A support plate 18 is mounted on the ties 15, and gauge plates 16, and has a wide portion disposed between the adjacent ends of the right-hand main-rail sections 10 and 11, and a narrow portion extending from the wide portion to the end of the right-hand side-track rail section 14. A similar support plate 19 is mounted on the rails and gauge plates, and has a wide portion disposed between the end of the left-hand main-track rail section 13 and the end of the left-hand side-track rail section 14 and a narrow portion extending from the wide portion to the end of the left-hand main-track rail section 12. Each of the support plates is provided with downwardly-extending flanges provided respectively along its longitudinal edges and with outwardly directed foot portions at the bottom or outer edges of these flanges with which the heads of the spikes 17 are engaged to secure the support plates firmly onto the ties and gauge plates of the track. Each of the support plates has, between its flanges, a flat top wall having a flat and substantially smooth upper surface which top wall is provided with two or more transversely extending grooves, as indicated at 20 and 21 in Figure 4, having undercut sides to give to the grooves a dovetail cross-sectional shape.

As particularly illustrated in Figure 5, the support plate 18 has a wide portion 22 provided with the transversely extending dovetailed grooves 20 and 21, a narrow portion 23, the inner side of which is in alignment with the inner side of the wide portion 22, and the distal end of which is provided with a bifurcated projection 24 to receive the web portion of the associated track rail section. This support plate is also provided with a short extension 25 at the end of the wide portion 22 opposite the narrow portion 23 which portion 25 is somewhat wider than the portion 23, but less wide than the portion 22, and also has its inner side or edge in alignment with the inner side of the portion 22, so that the support plate has a straight inner side or edge throughout its entire length. The portions 23 and 25 are elevated above the top surface of the portion 22 and

amount substantially equal to the thickness of the slide plates illustrated in Figure 6, and later to be described in detail. A bifurcated lug formation 26 is provided on the wide portion 22 at the end thereof from which the portion 23 extends, which lug formation is spaced from the extending portion 23 and positioned to engage the web of the main track rail section 10. The bifurcated formation 24 is elongated to receive a pin or rivet 53 by means of which an associated switch point is pivotally connected to this support plate, as will presently appear, and an arcuate groove 27 between the transverse grooves 20 and 21.

The support plate 19 is similar in all respects to the plate 18, except that the plate 19 is left-hand, whereas the plate 18 is right-hand. This plate has a wide portion 28 provided with spaced apart, transversely extending dovetailed grooves, as indicated at 20 and 21, an arcuate groove 27 between the dovetailed grooves, and has an elongated narrow portion 29 extending from one end, and a short narrow portion 30 extending from the opposite end thereof. The portions 29 and 30 are elevated above the upper surface of the portion 28 by an amount substantially equal to the thickness of the associated slide plate, and the portions 28, 29 and 30 are all aligned along their inner or right-hand edges to provide a straight inner edge or slide for the support plate. A bifurcated formation 31 is provided on the outer or distal end of the portion 29 to receive the web of the main track rail section 12, and is elongated to receive a pin or rivet 56 for pivotally connecting the associated switch point to the support plate. A bifurcated lug formation 33 is provided on the portion 28 at the end thereof adjacent the portion 29 and spaced from the portion 29 to receive the web of the side track rail section 14.

A slide plate 34 is slidably mounted on the upper surface of the wide portion 22 of the support plate 18, and a similar slide plate 35 is slidably mounted on the upper surface of the wide portion 28 of the support plate 19.

As is particularly illustrated in Figures 4 and 6, the slide plate 34 is provided, on its under side, with two spaced apart transversely extending battens 36 and 37 having undercut edges and slidably fitting the grooves 20 and 21 in the support plate 18. The slide plate 34 is a flat plate having a shape, in plan, substantially the same as the shape of the wide portion 22 of the support plate 18, and a rail head formation is secured onto the upper surface of the plate 34 and extends longitudinally of this plate adjacent the outer or right-hand edge thereof. The rail head formation 38 has a length substantially equal to the distance between the adjacent ends of the main rail sections 10 and 11, and is in alignment with these main rail sections when the switch is in the position illustrated in Figure 7, in which the main track is open.

The slide plate 34 is provided, near its center, with an elongated, keyhole shaped, aperture 39, and is provided on its inner edge with two spaced apart apertured lugs 40 and 41, and two connecting links or bars 42 and 43 are each pivotally connected at one end to a respective lug 40 or 41, and at their opposite ends are pivotally connected respectively to apertured lugs 44 and 45 provided on the inner edge of the left-hand slide plate 35.

A rail head formation 46 extends longitudinally of the slide plate 35 on the upper surface and adjacent the outer or left-hand edge thereof. This formation 46 has a length substantially equal to

the distance between the adjacent ends of the left-hand main rail section 13 and the left-hand side track rail section 14, and is in alignment with the rail sections 13 and 14 when the switch 5 is in the operative position illustrated in Figure 1, with the side track open and the main line closed. An apertured lug 47 projects from the outer edge of the plate 35 for connection to the bar 48 of a switch operating stand, not illustrated. The plate 35 is provided, near its center, with an elongated, keyhole shaped aperture 49 to receive a pin or rivet for attaching the corresponding switch point thereto, and this plate is provided on its under surface with spaced apart battens 50 and 51 having undercut edges and slidably receivable in the transverse grooves 20 and 21 in the support plate 19.

The groove and batten connections between the slide plates and the support plates permit the 20 slide plates to slide freely laterally of the wide portions of the support plates, but prevent the slide plates from being lifted or knocked off of the support plates and separated therefrom.

An elongated switch point 52 is pivotally connected at one end to the narrow portion 23 of the support plate 18 at the distal end of the portion 23 by the pin or rivet 53 and overlies the entire length of the upper surface of the support plate 18 and extends longitudinally across the slide 30 plate 34. A pin or rivet 54 extends through an aperture in the switch point and through the aperture 39 in the plate 34 to pivotally connect the switch point intermediate its length to the plate 34 intermediate the length of the latter, 35 the head of this rivet being movable in the groove 27 in the support plate 18. This switch point 52 has a tapered projection at its end opposite that receiving the pivot pin 53, and this projection is brought into contact with the inner side of the 40 right-hand main line rail section 11 when the switch is in the operative position illustrated in Figure 1, in which the side track is open, and the main line closed.

An elongated switch point 55 is pivotally connected, at one end, to the narrow portion 23 of the support plate 19 at the distal end of the portion 19 by the pin or rivet 56 extending through an aperture in the switch point and into the bifurcated portion 31 of the support plate 18. This switch point 55 extends across substantially the entire length of the support plate 19, and longitudinally across the slide plate 35. A pin or rivet 57 extends through an aperture in the movable switch point 55 and through the aperture 49 in the slide plate 35 to pivotally connect the switch point 55, intermediate its length, the head of this rivet being movable in the groove 27 in the support plate 19, to the slide plate 35 intermediate the length of the latter.

The switch point 55 has a tapered projection at its end opposite the end pivotally connected to the extension 29 of the support plate 19, and this tapered projection is brought into contact with the inner side of the main line rail section 33 when the switch is in position to open the main line and close the side track, as illustrated in Figure 7.

It will be noted that when the switch points are moved relative to the rail sections of the track the distance between these switch points and the adjacent rail head formations 38 and 46 is not decreased. Therefore, material such as snow, ice or sand will not be packed between the switch points and the adjacent rail formations, as occurs with conventional railway switch

connections, and the switch of the present invention will not clog so that it does not fully close when operating under such adverse conditions. By swinging the pivotally mounted switch points 52 and 55, the operation of the switch is substantially the same as the operation of conventional switches and the switch is of ample length to smoothly guide a train onto the side or spur track or to maintain it along the main line track, depending upon the setting of the switch. As the switch points and rail head formation are firmly supported on the wide flat support plates, the switch has ample strength and will safely support a train in either operative position of the switch.

In order to preclude bending the switch points incident to their being forced against the adjacent rail sections by train wheel pressure, a pair of suitable stops 58 and 59 is provided on the support plate 18 engaging the outer side of the switch point 52 when this switch point is in position against the rail section 11, and a pair of similar stops 60 and 61 is provided on the support plate 19 and bear against the outer side of the switch point 55 when this switch point is in engagement with the rail section 13.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A railway switch assembly comprising a pair of elongated support plates mounted in spaced apart relationship at respectively opposite sides of a railway main track at the junction of a side track with the main track, two slide plates slidably mounted one on each of said support plates, means interconnecting said slide plates for simultaneous movement laterally of said support plates, two railhead sections secured one on each of said slide plates for movement between a position in which one is in alignment with the ends of two spaced apart main track rails and the other is laterally displaced from alignment with adjacent ends of a main track rail and a side track rail and a position in which said one rail head section is laterally displaced from alignment with the associated main track rails and said other rail head section is brought into alignment with the ends of the associated main track and side track rails, two elongated switch points mounted one on each of said support plates, said switch points being pivotally connected each at one end to the corresponding support plate at a location spaced from the associated slide plate and overlying the associated slide plate and being alternatively engageable with the inner sides of the two spaced apart main track rails upon lateral movement of said slide plates relative to said support plates, means pivotally connecting each switch point to the corresponding slide plate, and means projecting from at least one of said slide plates for connection to a switch stand.

2. A railway switch assembly comprising two spaced apart elongated support plates each mountable on track ties between two adjacent ends of a corresponding main track rail and between one end of such main track rail and an adjacent end of a corresponding side track rail,

two slide plates supported one on each support plate intermediate the length of the latter, a first railhead formation on one of said slide plates movable into and out of alignment with the ends of the associated main track rail, a second railhead formation on the other of said slide plates movable into and out of alignment with the ends of an associated main track rail and an associated side track rail, two elongated switch points mounted one on each of said support plates, each of said switch points being pivotally connected at one end to the corresponding support plate at a location spaced from the associated slide plate, means pivotally connecting each switch point intermediate its length to the associated slide plate intermediate the length of the latter for alternative movement of said switch points toward and away from the corresponding main track rails at respectively opposite sides of the main track, and means interconnecting said slide plates for simultaneous and coextensive movements thereof laterally of said support plates.

3. A railway switch assembly comprising two spaced apart elongated support plates each mountable on track ties between two adjacent ends of a corresponding main track rail and between one end of such main track rail and the adjacent end of a corresponding side track rail, two slide plates supported one on each support plate intermediate the length of the latter, a first railhead formation on one of said slide plates movable into and out of alignment with the ends of the associated main track rail, a second railhead formation on the other of said slide plates movable into and out of alignment with the ends of an associated main track rail and an associated side track rail, two elongated switch points mounted one on each of said support plates, each of said switch points being pivotally connected at one end to the corresponding support plate at a location spaced from the associated slide plate, means pivotally connecting each switch point intermediate its length to the associated slide plate intermediate the length of the latter for alternative movement of said switch points toward and away from the main track rails at respectively opposite sides of the main track, means interconnecting said slide plates for simultaneous and coextensive movements thereof laterally of said support plates, and means interconnected between said support plates and the slide plates mounted thereon maintaining said slide plates against separation from said support plates while retaining freedom of relative sliding movement therebetween.

4. A railway switch assembly comprising two spaced apart elongated support plates each mountable on track ties between two adjacent ends of a corresponding main track rail and between one end of such main track rail and an adjacent end of a corresponding side track rail, two slide plates supported one on each support plate intermediate the length of the latter, a first railhead formation on one of said slide plates movable into and out of alignment with the ends of the associated main track rail, a second railhead formation on the other of said slide plates movable into and out of alignment with the ends of the associated main track rail and the associated side track rail, two elongated switch points mounted one on each of said support plates, each of said switch points being pivotally connected at one end to the associated support plate at a location spaced from the associated slide plate, means pivotally connecting each switch point intermediate

ate its length to the associated slide plate intermediate the length of the latter for alternative movement of said switch points toward and away from the main track rails at respectively opposite sides of the main track, and means interconnecting said slide plates for simultaneous and coextensive movements thereof laterally of said support plates, each of said support plates having a wide intermediate portion receiving the associated slide plate and narrow end portions elevated above said intermediate portion a distance

substantially equal to the thickness of the slide plate.
